UNITED STATES PATENT OFFICE.

JAMES W. REYNOLDS, OF CHESTER, NEBRASKA.

RAIL-JOINT.

1,105,697.

Specification of Letters Patent.

Patented Aug. 4, 1914.

Application filed April 2, 1914. Serial No. 829,109.

To all whom it may concern:

Be it known that I, JAMES W. REYNOLDS, a citizen of the United States, residing at Chester, in the county of Thayer and State 5 of Nebraska, have invented a new and useful Rail-Joint, of which the following is a specification.

The present invention appertains to rail joints, and aims to provide a rail joint embodying angle or splice bars of novel construction or formation which will enhance 10 the efficiency of the joint.

The present invention comprehends the provision of a rail joint, which will be of 15 such construction, as to effectively support the rail ends against depression, due to the hammering and strains to which they are subjected when traversed by a train, the present structure being capable of withstanding 20 the wear and tear incident to rolling stock.

Another object of the present invention, is to provide in a rail joint, novel means for holding the bolts in place.

Another object of the invention is to provide the angle or splice bars with novel 25 means for accommodating the spikes and their heads, whereby the efficiency of the device will be enhanced.

It is also within the spirit of the present 30 invention, to provide angle or splice bars, of comparatively simple and inexpensive construction, which may be readily manufactured, and which will be convenient, 35 practical and efficacious in their use.

With the foregoing and other objects in view which will appear as the description 40 proceeds, the invention resides in the combination and arrangement of parts and in the details of construction hereinafter described, it being understood that changes in the precise embodiment of the invention herein disclosed can be made within the scope of 45 what is claimed without departing from the spirit of the invention.

The invention has been illustrated in its preferred embodiment in the accompanying drawings, wherein—

Figure 1 is a side elevation of the improved rail joint, the spikes being removed. 50 Fig. 2 is an enlarged cross section taken through the joints.

In the drawings, the rails have been designated by the numeral 1, the rail ends meeting in the usual manner.

The joint includes a pair of opposite angle or splice bars 2 disposed at the opposite sides of the rail ends, each of the angle or splice bars 2 including an upstanding flange or fish plate 3 and a lower outturned flange 55 4. The upstanding flanges or fish plates 3 are provided with inner longitudinal ribs 5 along their upper and lower edges, which are arranged to engage the webs of the rails. The upper sides of the fish plates or flanges 60 3 are arranged to fit snugly under the heads or treads of the rails, while the lower flanges 4 are seatable snugly on the base flanges of the rails. The outer faces of the fish plates or flanges 3, adjacent the upper or free edges 65 70 of the fish plates or flanges, are arranged to be approximately flush with the sides of the rail heads or balls when the bars 2 are applied, as clearly seen in Fig. 2.

The outer remote sides of the fish plates 75 or flanges 3 of the splice bars, are provided with thickened or enlarged portions 6, which which extend longitudinally of the splice bars, and which extend to and are integral with the lower flanges 4, the upper edges of 80 the thickened or enlarged portions 6 being spaced below the upper edges of the fish plates or flanges 3. The faces of the enlarged portions 6 are preferably vertical or 85 parallel with each other.

Each of the splice or angle bars 2 is further provided within the crotch or corner between the flanges with a longitudinal rib 7.

The fish plates or flanges 3 are clamped against the sides of the rail ends, by means 90 of the usual bolts 8, which are passed through suitable apertures or openings 8^a provided in the fish plates or flanges 3 and the webs of the rails, the heads 9 of the bolts being square, as illustrated, and having certain 95 of their sides engaging upon the rib 7 of one splice bar 2. This prevents the bolts from rotating, as will be obvious. The heads 9 of the bolts seat against the corresponding thickened portion 6 of the respective splice 100 bar, and nuts 10 are threaded upon the ends of the bolts. To lock the nuts 10 against rotation, and to enable the nuts 10 to clear the rib 7 of the corresponding splice bar,

spring or lock washers 11 are interposed between the nuts 10 and the thickened portion 6 of the corresponding splice bar, whereby when the nuts 10 are tightened, the washers 11 will lock them against unscrewing, and furthermore, the washers 11 will space the nuts 10 sufficiently from the thickened portion 6 of the corresponding splice bar, to permit the nuts to be tightened without the 10 interference of the adjacent rib 7.

The outer or free edges of the lower flanges 4 of the splice bars are provided with suitably arranged notches or slots 12 for the reception or engagement of the spikes 13, 15 and the ribs 7 are provided with notches or slots 14 complementing the notches or slots 12, and adapted to receive the noses or projecting ends of the spike heads 15, as suggested in Fig. 2. In this manner, the bars 20 may be spiked to the ties, in a highly efficient manner, the notches or slots 12 and 14 accommodating the spikes and their heads in a peculiar manner, to increase the rigidity of the joint.

25 It is to be understood, of course, that the apertures or openings for the bolts may be arranged at various or suitable positions, according to the circumstances, and the slots or notches 12 and 14 may also be arranged 30 at suitable positions, they being preferably offset with respect to the bolt holes.

The present angle or splice bars may be readily applied to the rail ends, and when the splice bars are spiked to the ties, the 35 joint will be supported and braced in an efficacious manner, to prevent the injurious depression of the rail ends due to the hammering or jars to which the joint is subjected when in use.

40 The present bars may be constructed of various sizes and proportions, to accommodate various styles of rails.

Instead of employing the square headed bolts 8, as illustrated in the drawings, it

will be manifest that the common round 45 headed bolts may be employed, if desired.

Having thus described the invention, what is claimed as new is:

1. In combination, a pair of angle bars having lower and upstanding flanges, and 50 having longitudinal ribs within the crotches between the said flanges, bolts engaged through the said upstanding flanges, nuts threaded upon the bolts, and a lock washer disposed on each bolt between the corresponding nut and upright flange, the bolt heads and washers being disposed above the said ribs and seating against the said upright flanges, each bolt head engaging the corresponding rib to prevent the rotation of 60 the bolt, and each washer spacing the corresponding nut from the respective rib to clear the same.

2. In combination, a pair of angle bars including lower and upstanding flanges, and 65 having longitudinal ribs within the crotches between the said flanges, bolts engaged through the said upstanding flanges, nuts threaded upon the bolts, a lock washer disposed on each bolt between the respective nut 70 and upstanding flange, the bolt heads and washers being disposed above the ribs and seating against the said upright flanges, each bolt head engaging the respective rib to prevent the rotation of the bolt, each washer spacing the corresponding nut from the respective rib, the said lower flanges and ribs having complementing notches, and spikes engaging the notches of the said lower flanges and having the projecting ends of the heads 80 engaging the notches of the said ribs.

In testimony that I claim the foregoing as my own, I have hereto affixed my signature in the presence of two witnesses.

JAMES W. REYNOLDS.
